(57) **CLAIM**

The ornamental design for a D-ring cord attachment point, as shown and described.

DESCRIPTION

FIG. 1 is a front perspective view of our D-ring cord attachment point;

FIG. 2 is a rear perspective view thereof;

FIG. 3 is a front elevational view thereof;

FIG. 4 is a rear elevational view thereof;

FIG. 5 is a left side elevational view thereof, the right side elevational view being a mirror image thereof;

FIG. 6 is a top plan view thereof; and,

FIG. 7 is a bottom plan view thereof.
